US00D545983S

(12) **United States Design Patent** (10) **Patent No.:** **US D545,983 S**
Bennett, Jr. (45) **Date of Patent:** **** Jul. 3, 2007**

(54) **COMPACT DEVICE FOR ILLUMINATING A FLAT SURFACE**

(75) Inventor: **James F. Bennett, Jr.**, Nantucket, MA (US)

(73) Assignee: **Lightwedge, LLC**, Nantucket, MA (US)

(**) Term: **14 Years**

(21) Appl. No.: **29/238,922**

(22) Filed: **Sep. 23, 2005**

(51) **LOC (8) Cl. 26-02**

(52) **U.S. Cl. D26/37**

(58) **Field of Classification Search** D26/37-50; 362/157, 158, 171-174, 183-208

See application file for complete search history.

Primary Examiner—Marcus A. Jackson

(74) *Attorney, Agent, or Firm*—Nixon Peabody LLP; Tim L. Brackett, Jr.

(57) **CLAIM**

The ornamental design for a compact device for illuminating a flat surface, as shown and described.

DESCRIPTION

FIG. 1 is a perspective view of an illustration of a compact device for illuminating flat surface;
FIG. 2 is a left side view thereof;
FIG. 3 is a right side view thereof;
FIG. 4 is a top view thereof;
FIG. 5 is a rear end view thereof;
FIG. 6 is a bottom view thereof; and,
FIG. 7 is a front end view thereof.
